CYCLE FOR A TOY DOLL

Kosei Kato, Tokyo, Japan, assignor to Tomy
Kogyo Co., Inc., Tokyo, Japan

Filed Apr. 5, 1974, Ser. No. 458,193

Term of patent 14 years

Int. Cl. D21—01

U.S. Cl. D34—15 AJ

FIG.1

FIG.2

FIG. 3

FIG. 4

FIG. 5

FIG. 6

FIG. 1 is a side elevational view of a cycle for a toy doll embodying my new design;

FIG. 2 is a top plan view thereof;

FIG. 3 is a perspective view thereof;

FIG. 4 is a front elevational view thereof;

FIG. 5 is a rear elevational view thereof; and

FIG. 6 is a bottom plan view thereof.

I claim:

The ornamental design for a cycle for a toy doll, as shown.
